(57) **CLAIM**

The ornamental design for a laptop computer, as shown and described.

DESCRIPTION

FIG. 1 is a top, front, and left side perspective view of a laptop computer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the encircled portion '8' in FIG. 1 thereof.

The short-dashed broken lines depict portions of the laptop computer that form no part of the claimed design.

The long-dashed, short-dashed broken lines shown in FIGS. 1 and 8 depict the limits of the enlarged view and form no part of the claimed design.
